UNITED STATES PATENT OFFICE

SIDNEY E. ANDERSON, OF BROOKLYN, NEW YORK, ASSIGNOR TO WESTERN ELECTRIC COMPANY, INCORPORATED, OF NEW YORK, N. Y., A CORPORATION OF NEW YORK

LOOP ANTENNA

Application filed May 10, 1923. Serial No. 637,941.

This invention relates to loop antennæ.

An object of this invention is to provide a novel and improved form of loop antenna wherein symmetry in the physical parts and more especially symmetry in the electrical characteristics thereof are secured.

Another object of this invention is to provide a loop antenna having high efficiency over a wide range of wave lengths.

10 An additional object concerns the provision of improved devices associated with a loop antenna whereby rotation is permitted without affecting the physical or electrical symmetry, thereof.

15 A feature of this invention relates to an improved portable, rotatable loop antenna whereby strength and compactness are obtained and whereby the conductors of the loop are held in equal spacing and under tension.

20 The antenna of this invention may comprise a substantially rectangular loop formed with a plurality of equally spaced turns of a continuous conductor wound in solenoidal

25 form about a supporting frame. The frame may, for example, comprise symmetrically intersecting arms of full elliptical form rotatably supported by a circular base having contact members arranged to make continuous

30 connection to a plurality of concentric rings connected to the loop conductor. The concentric rings are preferably arranged in the same plane and so placed that the capacity between an outer ring and a common intermediate ring is equal to the capacity between an inner ring and the common intermediate ring.

35 By considering the following detailed description, in connection with the accompanying drawings, a more comprehensive idea of the nature and advantages of this invention will be obtained.

Fig. 1 of the drawings shows a front view of one practical form of the loop antenna. Fig. 2 is a side view of the antenna of Fig. 1. Fig. 3 shows a front view of another type of loop antenna which embodies this invention. Fig. 4 is a detail view in section on line 4 of Fig. 5 showing the method of connecting the loop conductors to the slip rings. Fig. 5 is a

view in cross section of the antenna base. Fig. 6 shows the arrangement of the slip rings. Fig. 7 shows the practical application of this invention to a radio receiving circuit.

In Fig. 1, a continuous conductor 10 which may be of the well known Litzendraht wire is wound in equally spaced turns upon the frame 11. This frame comprises arms 12 and 13 intersecting at right angles, which arms may be constructed in full elliptical form similar to a well known type of vehicle spring. These arms are preferably of insulating material, for example, birch or maple wood. They are fitted at their intersection by dove-tailed construction and held in place by attachment to a block 14 inserted in the common space between their sides. A circular base plate 15 preferably of hard rubber is attached to the lower end of arm 12 of frame 11 as shown. Plate 15 normally rests upon and is pivoted to an insulating base 16 which may, for example, be birch or maple wood. In order to provide a more rigid construction, a stiffening member 17 which may be a wedge-shaped post of birch or maple wood is fitted in the lower half of arm 12.

In Fig. 2 is shown a side view of the antenna of Fig. 1 illustrating the arrangement of the conductors 10. These conductors are carried in equally spaced grooves formed on the outer edge of fan-shaped plates 18 attached to the two ends of arm 13 and the upper end of arm 12. At the lower end of arm 12, conductors 10 pass through equally spaced holes 19 in the fan-shaped plate 24 joining base plate 15 to the lower end of arm 12. Plates 18 and 19 are preferably of insulating material which may be, for example, phenol fiber.

The conductors 10 form a continuous loop, the ends of which are conductively connected to suitable terminals 20 and 21 attached to the fiber plate 24 interposed between the circular plate 15 and the arm 12 as shown in detail in Figs. 4 and 5. The midpoint of loop conductors 10 is conductively connected to a similar terminal 22. Terminal 21 is electrically connected to conducting pivot 25 of Fig. 5. Terminal 20 connects to individual slip ring 26 by way of lug 35 and screws 23 and 28 as

shown in Fig. 4. Terminal 22 connects to slip ring 27 by way of lug 45 and screws 33 and 38 in a like manner as shown in Fig. 5. Terminal 21 connects to pivot 25 by way of 5 a threaded projection 43 thereon screwed to lug 55. Screws 23 and 33 and pivot 25 serve also to fasten base plate 15 to fan-shaped plate 24. The slip rings 26 and 27 and the pivot 25, which may be of any suitable metal 10 for example brass, are attached to the plate 15 concentric with pivot 25 which is at the center of the plate.

An antenna constructed in accordance with 15 this invention having the following approximate dimensions has been found to operate satisfactorily over a range of wave lengths of approximately 600 meters in the neighborhood of 400 meters wave length.

The arms 12 and 13 are approximately 20 thirty inches long making the loop 24 inches square. The fan shaped plates are approximately four inches wide at the outer edge, two inches wide at the inner end and one fourth inch thick.

25 Twelve turns of a continuous conductor of 81 strand No. 38 Litzendraht wire spaced five sixteenths of an inch apart composed the loop.

In Fig. 3, a form of loop antenna similar 30 in construction to that of Fig. 1 is shown. The construction, differs, however, in that the arms 12 and 13 may intersect at angles other than right angles. The supporting member or post 17 in this instance is attached 35 to the frame 11 at a point between the arms 12 and 13 which are consequently positioned obliquely thereto. The post 17 is so placed as to bisect the angle between the arms and is symmetrical with respect to them.

40 The base plate 15 of this antenna is attached to the post 17 instead of to the arm 12 as in the antenna of Fig. 1. In both antennae, the base plate 15 is so placed that its center is on the axial line of the frame and 45 supporting post 17 and whereby a symmetrical structure is obtained.

Fig. 5 shows also a cross-section of circular base 16 through the center of which is inserted cylindrical conducting bushing 30, which cooperates with pivot 25. In base 16, 50 parallel to the cylindrical bushing 30 are conducting brushes 34 positioned to make electrical connection with slip rings 26 and 27, respectively. Brushes 34, which may be of conducting mesh are held yieldingly in contact with rings 26 and 27 by individual springs 36, held in place by screws 40 threaded to bushings 32 which encase the respective brushes and springs. Bushings 30 and 32 55 constitute suitable terminals for connecting the antenna conductor to external circuits. A rectangular slot 39 is provided on the bottom surface of base 16, through which a conducting cord may pass. Base 16 contains a hollow portion 41 to provide access to the

terminals 30 and 32 and to provide space for a conducting cord. If desired, however, a cord may be connected directly to the terminals 20, 21 and 22.

Fig. 6 is a plan view of plate 15 showing 70 the arrangement of the slip rings 26 and 27 and pivot 25. One object of this invention concerns the novel arrangement of slip rings 26 and 27 and pivot 25 whereby the capacity between rings 26 and 27 is made equal to the capacity between ring 27 and pivot 25. The proper spacing of the slip rings and central pivot in order to obtain this balance of capacity may be calculated from the formula 75

$$C = \frac{K}{2 \log_e \frac{R_2}{R_1}}$$

80 which is an expression for the capacity between two concentric rings, where C is the capacity, K is the dielectric constant, R₂ the radius of the outer ring and R₁ the radius of the inner ring. In this formula it is apparent that if we wish to make the capacity between one pair of concentric rings equal to 85 the capacity between another pair of concentric rings of different radii, the ratio between the radii of each pair of concentric rings must be the same.

90 Referring to Fig. 6, R₁ is the radius of the flange of the central supporting pivot 25, which constitutes one ring, R₂ is the inside radius of inner ring 27, R₃ the outside radius of inner ring 27, and R₄ the inside radius of outer ring 26. The capacity between the two 95 rings will thus be equal to the capacity between the inner ring and the central pivot if the relation 100

$$\frac{R_1}{R_2} = \frac{R_3}{R_4}$$

105 obtains. When the rings are spaced in accordance with the above ratios a substantially exact balance between the capacity of the rings and the capacity of the inner ring and the central supporting shaft will be obtained although the length of the rings considered as cylinders is small as compared to their diameters. In the usual manner of constructing slip rings and brushes, the rings have been placed one above the other upon the extension of the shaft supporting the loop. This form of construction, however, adds considerable bulk to the antennae. It is one purpose of this invention to produce a portable antenna of as small size as possible and the form of construction described accomplishes this purpose.

110 In Fig. 7 is shown a radio receiving circuit with the loop antenna 50 of this invention connected to the detector D₁ by a multiple conductor 51 for the purpose of receiving wave energy. The detector D₁ comprises a three-electrode tube 52 having its grid and filament connected to an input circuit con- 115

taining a polarizing battery 53, a portion of the turns of loop antenna 50, and one winding of transformer 54. Generator 55 is associated with the second winding of transformer 54 and supplies oscillations to the input circuit at a frequency different from that of the receiving waves whereby a beat or intermediate frequency is produced in detector D_1 in a manner now well understood.

10 The output circuit of the detector D_1 comprises the plate of tube 52, primary winding of transformer 56, battery 57 and the filament of tube 52. The plate of tube 52 is also connected by way of a low capacity 15 condenser 58 with a portion of the turns of loop antenna 50 which are in close inductive relation to the portion associated with the amplifier input circuit. The condenser 58 is of such value as to balance the internal grid-plate capacity of tube 52 whereby undesired regenerative effects, such as 20 singing are prevented.

A variable condenser 59 connected in parallel with the loop antenna forms a resonant, 25 circuit therewith capable of being adjusted to the frequency of incoming electromagnetic waves.

For obtaining low frequency speech currents from the modulated intermediate frequency radio waves, a second detector D is 30 associated with the detector D_1 and the antenna 50 connected thereto, by means of an intermediate frequency amplifier IFA. The intermediate frequency amplifier IFA receives energy from the output circuit of detector D_1 through the transformer 56 and supplies energy through a resonant circuit 63 formed by a condenser and the primary winding 35 of transformer 60, which resonant circuit is tuned to the intermediate frequency. The 40 tuned circuit 63 serves to prevent the admission of extraneous frequencies into the input circuit of detector D .

The input circuit of detector D is supplied 45 with waves of the intermediate frequency from the resonant circuit 63 through transformer 60. This input circuit contains in addition to the secondary winding of transformer 60, a grid leak 61 consisting of a resistance and capacity in parallel.

A receiver 62 shunted by a condenser 64 is 50 connected to the output circuit of the detector D for obtaining the reproduced signal speech sounds from the demodulated electrical currents in the output circuit. The condenser 64 offers low impedance to radio frequency currents but high impedance to audio frequency currents.

This system operates most successfully 55 when the circuits are electrically symmetrical with respect to ground. The loop antenna 50 maintains its capacity constant and balanced even when being rotated and thus prevents change of tuning or unbalance of the circuits. Hence, the use of a symmetri-

cal loop antenna such as described herein is essential to the proper functioning of the circuit.

Although the principles of this invention have been illustrated and described in connection with certain specific structures, it is not intended that the present disclosure is to be limited thereto, but only in so far as pointed out in the following claims.

What is claimed is:

1. A radio receiving system comprising a space discharge device having a cathode, anode and control electrode, a wave collecting conductor comprising a rotatable loop antenna having terminals connected respectively to said electrodes through a plurality of slip rings, the portions of said conductor included between one of said terminals and the other two terminals respectively being electrically balanced.

2. A radio receiving system comprising a space discharge amplifier having a cathode, anode and control electrode, a rotatable loop antenna having a plurality of slip rings through which its outer terminals are connected to said anode and control electrode and an intermediate terminal connected to said cathode, the portion of said loop connected between the cathode and anode being electrically balanced with respect to the portion included between the cathode and control electrode.

3. The combination in a rotatable loop antenna of a plurality of contact rings conductively associated with the turns of said loop, 100 said contact rings being so arranged that the capacity between one ring and each of the others is made equal.

4. A radio receiving system comprising a space discharge amplifier having a cathode, anode and control electrode, a loop antenna provided with a plurality of slip rings, said slip rings being connected to end terminals and an intermediate terminal of said loop and to the anode, control electrode, and cathode, respectively of said amplifier, said rings being arranged in such manner that the capacity of one with respect to each of the others is made equal.

5. In a symmetrical loop antenna, the combination of a rotatable frame and a stationary base, said frame having concentric planar rings cooperating with contact members in said base, said contact rings being so spaced that the capacity between an intermediate ring and an inner and an outer ring is equal.

6. The combination in a rotatable loop antenna of a closed conducting loop having outer and middle terminals connected to individual slip rings on a supporting base, said base having contact members cooperating with said slip rings, said contact members comprising conducting brushes slidably fitted in a metallic bushing and yieldingly pressed against said slip rings under the action of a

spring, said rings having radii in accordance with the ratios

$$\frac{R_1}{R_2} = \frac{R_3}{R_4}$$

5 7. A radio receiving system comprising a space discharge amplifier having a cathode, anode and control electrode, a rotatable loop antenna having equal portions connected between said cathode and anode, and cathode and control electrode, respectively, said portions cooperating with a balancing reactance to prevent singing in said amplifier and slip rings for effecting said connection whereby 15 said antenna may be rotated without causing said amplifier to "sing".

8. A loop antenna comprising a rotatable member, a stationary member, said rotatable member comprising a framework having full 20 elliptical arms intersecting at right angles, a closed conducting loop supported by said frame, a circular base plate attached to the end of one of said arms, and a stiffening post fitted to the last mentioned arm, whereby 25 by said rotatable member may be rigidly supported.

9. A rotatable loop antenna, comprising a circular base, a rotatable frame mounted upon said base, a coiled conductor mounted 30 upon said frame, and a plurality of concentric planar rings, said rings being connectively associated with the terminals of said coiled conductor and with a mid-tap thereto whereby electrical connection may be made to said loop during rotation and a balance in the electrical reactance of one of said rings with respect to the remainder thereof is maintained.

10. A loop antenna of substantially rectangular form comprising a plurality of equally spaced turns of a continuous conductor, said conductor being supported upon a frame, comprising a pair of substantially elliptical trusses dovetailed at their respective midpoints and attached to a central block, whereby vibration of said frame is substantially prevented.

11. The combination with a radio receiving circuit of a space discharge tube having a cathode, anode and control electrode, a loop antenna having low distributed capacity, said antenna comprising a winding having a plurality of widely spaced turns of a continuous conductor, said winding being split by a mid-tap connected to an annular ring, said ring being connected to said cathode and associated with an inner and an outer ring connected respectively to said anode and control electrode and to respective terminals of said winding and so arranged that the capacity between said first mentioned ring and said inner and outer rings respectively is equal.

12. The combination in a loop antenna of a conductor coil in two sections, an insulating

supporting frame and a base, said frame being rotatable upon said base and comprising means for making adjustable connection to the sections of said coil so that capacity balance between said sections is maintained.

13. A portable wave receiving device comprising a conducting loop, an insulating frame comprising full elliptical arms rotatably mounted upon a base having brushes cooperating with means associated with said arms for making connection to said loop, said means comprising a plurality of conducting elements, the capacity between adjacent pairs of elements being equal.

14. A loop antenna of substantially rectangular form comprising a plurality of equally spaced turns of a continuous conductor supported upon a frame comprising a pair of substantially elliptical trusses dovetailed at their respective midpoints, one of said trusses having a stiffening member fitted thereto whereby vibration is substantially prevented.

In witness whereof, I hereunto subscribe my name this 9th day of May, A. D., 1923.
